UNITED STATES PATENT OFFICE.

JOSEPH T. L. LAVAGETTO, OF PORTLAND, OREGON.

SHIP CONSTRUCTION.

Application filed October 26, 1922. Serial No. 596,981.

To all whom it may concern:

Be it known that I, JOSEPH T. L. LAVAGETTO, a citizen of the United States, residing at Portland, in the county of Multnomah 5 and State of Oregon, have invented a new and useful Ship Construction, of which the following is a specification.

My invention relates to improvements in ship construction for wooden vessels in 10 which the outer planking is seated in metal ribs, and in which the oakum is held in a longitudinal groove in the long edge of the plank.

The objects of my invention are:

15 First, to strengthen the hull by means of metal ribs.

Second, to afford superior protection against damage.

20 Third, to make provisions for easy replacement of damaged planks.

Fourth, to provide means for retaining the oakum in the seams.

25 Further objects and advantages will be found in the specifications and particularly 75 pointed out in the appended claims.

I attain these objects with the mechanism illustrated in the accompanying drawing, in which:—

Fig. 1 is an elevation of a ship's hull.

30 Fig. 2 is a detail of the metal rib.

Fig. 3 shows the oakum between two planks.

Similar numerals refer to similar parts throughout the several views.

35 The wooden rib 1 of the frame work is first covered with the customary planks 2. On top of these planks is placed a metal rib whose bottom flange 3 reposes in a groove in the planks 2 to be flush with the outer 40 face. A bolt 4 holds the metal rib to the wooden rib. From the web 5 of the metal rib extends a top flange 6 in the direction of the stern of the ship so that in case of collision the force of the impact is taken up 45 rather by the stronger web than by the weaker edge of the top flange. The channel formed by the top and bottom flanges is utilized to hold one end 7 of the outer or cover plank 8, the other end 9 of the same plank is fitted 50 into the angle between the bottom flange and web of the adjacent metal rib and securely held in place by a lag screw 10. Oakum 11 is calked into the joint where the end 9 abuts the web 5. In case of repair it is thus

an easy matter to remove the damaged plank 55 and insert a new one.

The outer planks 8 are further provided with a groove in one edge for the reception of a strand of oakum 12 (Fig. 3). The strand should be thick enough to fill the joint 60 completely when two planks are pressed together. A loss of the oakum is thereby absolutely avoided.

A copper sheathing 13 covering the hull below the water line protects the wood work 65 against damage by teredos, barnacles and other subaquatic animals. The copper sheathing should extend to the anchor hole 14, so that the planks will not be marred by the anchor. 70

Having thus described my invention it will be seen that my objects have been accomplished, and, though I have shown the preferred form of construction, I reserve to myself the right to make minor changes providing I do not violate the spirit and principle of my invention. 75

I claim:

1. A copper sheathed wooden hull, comprising wooden ribs, inner planks secured 80 on the wooden ribs, metal ribs on the outer surface of the inner planks adapted to form a seat for the outer planks, and outer planks having one edge grooved for the reception of oakum. 85

2. A copper sheathed wooden hull, comprising wooden ribs, a double layer of planks, and metal ribs securing the outer layer of planks, said metal ribs including a bottom flange, a web, and a top flange. 90

3. A copper sheathed wooden hull, comprising wooden ribs, a double layer of planks having one edge grooved for the reception of oakum, and metal ribs securing the outer layer of planks, said metal ribs including a bottom flange, a web, and a top flange. 95

4. A copper sheathed wooden hull comprising wooden ribs, a double layer of planks having one edge grooved for the reception of oakum, and metal ribs holding 100 said planks to the wooden ribs, said metal ribs including a bottom flange, a web at the center line of the bottom flange, and a top flange extending from the web toward one side. 105

5. A copper sheathed wooden hull, comprising metal ribs, having a bottom flange,

a web, a top flange extending at right angles from the web toward the stern, and planks having one end held between the top and bottom flange and the other end reposing in the corner formed by the bottom flange and web of the adjoining metal rib.

5 6. A copper sheathed wooden hull, comprising wooden ribs, metal ribs attached to

the outside of the wooden ribs, a double layer of planks held in place by the wooden and metal ribs, and a longitudinal groove in the long edge of each plank for the reception of oakum.

Signed by me at Portland, Ore., this 21st day of October, 1922.

J. T. L. LAVAGETTO.
